GABRIEL P. B. HOYT, OF NEW YORK, N. Y.

VALVE MECHANISM.

1,180,042.

Specification of Letters Patent. Patented Apr. 18, 1916.

Application filed July 3, 1915. Serial No. 37,885.

To all whom it may concern:

Be it known that I, GABRIEL P. B. HOYT, a citizen of the United States, and a resident of the city of New York, Jamaica, 5 borough of Queens, in the county of Queens and State of New York, have invented a new and Improved Valve Mechanism, of which the following is a full, clear, and exact description.

10 The object of the invention is to provide a new and improved valve mechanism more especially designed for use on internal combustion engines and arranged to govern the admission of the explosive mixture and 15 the exhaust of the products of combustion, and to prevent leakage of the explosive mixture during the compression and explosive periods thus rendering the engine highly efficient.

20 In order to accomplish the desired result, use is made of a valve seat, a valve movable on the said valve seat and mechanical means for moving the said valve firmly onto the said seat during the closing movement 25 of the valve and for allowing the valve to move out of firm contact with the said seat during the opening movement of the valve.

A practical embodiment of the invention is represented in the accompanying drawings forming a part of this specification, in which similar characters of reference indicate corresponding parts in all of the views.

Figure 1 is a sectional side elevation of the valve mechanism as applied and showing the admission valve closed and the exhaust valve open, the section being on the line 1—1 of Fig. 2; Fig. 2 is a cross section of the valve mechanism on the line 2—2 of Fig. 1; and Fig. 3 is a sectional side elevation of the same on the line 3—3 of Fig. 2.

In the cylinder A of the internal combustion engine reciprocates the piston B and the upper end A' of the cylinder A forms the working chamber and is provided at 45 opposite sides with admission ports *a* and exhaust ports *b*, the said ports leading into recesses A², A³ formed externally in the sides of the cylinder A. The recesses A², A³ are closed by an admission chest C and 50 an exhaust chest D, of which the admission chest C is connected by a pipe E with a source of explosive mixture supply, and

from the chest D leads an exhaust pipe E' for carrying off the products of combustion. The walls C' and D' of the chests C 55 and D, and covering the recesses A², A³, are formed at their outer faces into valve seats for an admission valve F and an exhaust valve F', both alike in construction and provided with ports *c* and *c'* adapted 60 to move into and out of register with the port *a* or *b* and with ports *d* or *d'* formed in the wall C' and D'. Each of the valves F and F' is provided with a post F² extending through a slot *e* formed in the wall 65 C' (or D'), the post being preferably fastened in place on the valve F by a suitable bolt F³, as plainly indicated in the drawings. Each post F² is connected by a link G with a rod H mounted to slide in the 70 bottom of the corresponding chest C or D, and this rod H is connected with the usual cam or other mechanism for imparting movement to the rod with a view to move the corresponding valve F or F' into open 75 position, the return of the valve into closed position being accomplished by a spring H'. The mechanism for moving the valves F and F' is the same as now generally employed for actuating puppet valves of 80 internal combustion engines, and hence further description of the same is not deemed necessary.

Each post F² is provided on opposite sides with trunnions I on which are journaled friction rollers J adapted to travel on inclines K attached to or forming integral parts of the wall C' or D' and extending within the corresponding chest C or D. The inclines K are so arranged that when 90 the valve F or F' is moved into open position the friction rollers J travel down the inclines, but when the valve F or F' moves into closed position the friction rollers J travel up the inclines thus drawing the 95 valve F or F' firmly onto its seat on the outer face of the corresponding wall C' or D'. Thus during the time the valve F or F' is closed it is firmly held on its seat on the corresponding wall C' or D', that is, 100 during the time the compression and the explosion take place within the cylinder A. When the valve F or F' is in closed position as described the force of the compression

as well as that of the explosion within the cylinder A exerts a pressure on the closed valves F and F' to aid the friction rollers J in holding the valves to their seats. When 5 the valve F or F' begins to move into open position, the friction rollers J immediately release the valves from their seats thus allowing an easy opening of the valves. It is understood that when the valve F is open

10 the explosive mixture is drawn into the cylinder A from the chest C and when the valve F' is in open position the products of combustion pass from the cylinder by way of the registering ports e, d, and e', d', into 15 the chest D and out of the same by way of the exhaust pipe E'. It is understood that the link G connecting the post F² with the corresponding rod H permits the movement of the valve F or F' toward and from its 20 seat without danger of bending the rod H. In practice, the post F² is preferably fastened to the corresponding valve F or F' by a bolt F³, but I do not limit myself to this particular construction.

25 The valve mechanism shown and described is very simple in construction and lubrication of the valves F and F' is not necessary, and any wear on the valves or their seats is readily taken up by the friction rollers J traveling on the inclines K so that the valves are held firmly to their seats during the time the valves are in closed 30 position.

Having thus described my invention, I 35 claim as new and desire to secure by Letters Patent:

1. A valve mechanism for internal combustion engines, comprising a chest having an exterior valve seat adjacent to and spaced 40 from the engine cylinder, a valve movable on the said seat, means for imparting movement to the said valve, and mechanical means within the said chest for pressing the said valve firmly onto its seat during the 45 closing movement of the valve and to allow the valve to move out of firm contact with the seat during the opening movement of the valve.

2. A valve mechanism for internal combustion engines, comprising a chest having a wall provided with a port, the outer face of the wall forming a valve seat, a slide valve mounted to slide on the said valve seat and having a port adapted to move into and 50 out of register with the said wall port, the said valve having a post extending into the said chest, means connected with the said post for imparting a sliding motion to the said valve to move the ports into and out of 55 the said register, and co-acting means on the said post and wall to draw the valve to its seat on the valve moving into closed position.

3. A valve mechanism for internal combustion engines, comprising a chest having a wall provided with a port, the outer face

of the wall forming a valve seat, a slide valve mounted to slide on the said valve seat and having a port adapted to move into and out of register with the said wall port, means for imparting a sliding movement to 75 the said valve to move the said ports into and out of register, and co-acting means on the said valve and wall to draw the valve to its seat on moving the valve into closed position.

4. A valve mechanism for internal combustion engines, comprising a chest having a wall provided with a port, the outer face of the wall forming a valve seat, a slide valve mounted to slide on the said valve seat 80 and having a port adapted to move into and out of register with the said wall port, the said wall having a slot, and the valve having a post extending through the slot into the chest, means connected with the 85 said post for imparting movement to the valve, an incline on the inner face of the wall, and a friction roller journaled on the post and engaging the said incline.

5. A valve mechanism for internal combustion engines, comprising a chest having a wall provided with a port, the outer face of the wall forming a valve seat, a slide valve mounted to slide on the said valve seat and having a port adapted to move into and 90 out of register with the said wall port, the said wall having a slot and the said valve having a post extending through the said slot into the chest, an actuating rod 95 slidable in the said chest, a link connecting the said rod with the said post, a friction roller on the said post, and an incline on the inner face of the said wall and engaged by the said friction roller.

6. In an internal combustion engine the 105 combination with a cylinder having a port, a chest held on the said cylinder and having a wall spaced from the cylinder, the wall being provided with a port and the face of the wall nearest the cylinder being spaced therefrom and forming a valve seat, a valve movable on the said valve seat and having a port 110 adapted to move into and out of register with the said cylinder port and the said wall port and mechanical means within the 115 said chest and connected with the said valve by way of the said wall to press the valve firmly onto its seat during the closing movement of the valve and to allow the valve to move out of firm contact with the said seat 120 during the opening movement of the said valve.

7. In an internal combustion engine, the combination with a cylinder having a port, a chest held on the said cylinder and having 125 a wall spaced from the cylinder, the wall being provided with a port and the face of the wall nearest the cylinder being spaced therefrom and forming a valve seat, a valve movable on the said valve seat and having a port 130

adapted to move into and out of register with the said cylinder port and the said wall port, means for imparting movement to the said valve, and means for drawing the said valve to its seat during the time the valve moves into closed position.

In testimony whereof I have signed my

name to this specification in the presence of two subscribing witnesses.
